UNITED STATES PATENT OFFICE.

WILLIAM H. LANDON, OF PRINCETON, CANADA.

IMPROVEMENT IN HEATING-STOVES.

Specification forming part of Letters Patent No. 124,496, dated March 12, 1872.

Specification describing a new and useful Improvement in Stoves, invented by WILLIAM H. LANDON, of Princeton, in the county of Oxford, in the province of Ontario and Dominion of Canada.

My invention consists of a combination of an interior fire-shell and a damper with that class of stoves comprised mainly of a horizontal elliptical shell with its major axis in a vertical plane, in such manner as to greatly economize the heat. It also consists of a novel arrangement of ventilating-damper.

Figure 1 is a transverse section of my improved stove, and Fig. 2 is a longitudinal section.

The said stove is composed of two end plates of cast-iron, of an oval form, the front one having an extension, B, forming a hearth and ash-pit, and near the bottom of the hinder one is an opening, C, for a ventilating-damper, D, and also for removing any ashes which may be deposited within the hot-air space. On the inner side of these plates, near their edges, a groove is formed in the casing to receive the outer shell, which is made of Russia or other suitable sheet-iron. Within the latter there is another parallel groove, extending about three-fourths the distance around the stove, to receive the inner shell or fire-plate E. The space between the shells, which I call the flame-flue, is about two inches, more or less. The inner shell or fire-plate E commences about the cen-

ter, vertically, of one side—say at F—and, curving downward under the fire-chamber, upward along the opposite side, terminates at the center of the top, where it is made, by means of a sharp reverse curve, to touch the outer shell, and also to divide the pipe-hole into two equal parts, G H. A semicircular damper, I, is placed here, with its crank-shaft lying parallel with and touching the top of the fire-plate, outside the pipe. This damper, turned in one direction, closes the direct communication G, between the fire-chamber and smoke-pipe, and forces the flame into the flame-flue and around shell E. When turned in the other direction, such connection is direct, and a strong draught is obtained for kindling the fire or quickening the combustion. The ventilating-damper is cast upon a shoe which fits the curve of the shell, on which it rests, and keeps the damper in position.

I do not limit myself to the oval or any particular form of stoves.

Having thus described my invention, I claim as new and desire to secure by Letters Patent—

The stove A, provided with corrugated lining E, dampers I and D, all as shown and described, and for the purpose set forth.

W. H. LANDON.
